(57) CLAIM

The ornamental design for a figurine, as shown and described.

DESCRIPTION

FIG. 1 is a front view of a figurine;
FIG. 2 is a rear view thereof;
FIG. 3 is a first side view thereof;
FIG. 4 is a second side view thereof; and,
FIG. 5 is a top view thereof.

The broken lines shown in the drawings illustrate portions of the figurine that form no part of the claimed design.
